UNITED STATES PATENT OFFICE.

SAMUEL W. BARNETT, OF GREENFIELD, INDIANA.

BROOM-SUPPORT.

SPECIFICATION forming part of Letters Patent No. 270,624, dated January 16, 1883.

Application filed October 7, 1882. (No model.)

To all whom it may concern:

Be it known that I, SAMUEL W. BARNETT, of the city of Greenfield, county of Hancock, and State of Indiana, have invented certain new and useful Improvements in Broom-Supports, of which the following is a specification.

As is well known, brooms when permitted to rest upon the brush end when not in use will soon become bent out of proper shape, and their value and efficiency thus seriously impaired.

The object of my said invention is to obviate this difficulty; and it consists in an attachment which may be adjusted to support the broom entirely from the floor, or to permit it to come in contact therewith in the ordinary manner, as will hereinafter be more particularly described.

Referring to the accompanying drawings, which are made a part hereof, and on which similar letters of reference indicate similar parts, Figure 1 is a front elevation of a broom provided with my attachment, said attachment being in position to keep the broom off the floor; Fig. 2, a side elevation of the same; and Fig. 3, a view like Fig. 1, except that the attachment is raised, so that the broom may be used without being affected thereby.

In said drawings, the portions marked A represent the broom-handle, B the broom, and C my attachment.

The several parts are or may be of any ordinary or approved form, except as hereinafter specified.

Eyes or loops a' a² are secured to the handle A, through which to pass the stem of the attachment C. These are preferably common screw-eyes, which enter the wood of the handle, and are thus secured in position. The eye a' should be screwed in a little farther than the eye a², as shown, so as to bear tightly against the attachment C, for the purpose hereinafter explained.

The attachment or support C is formed of heavy wire, preferably of a quality that will

spring somewhat without bending, and should be bent into a loop, c, at the upper end, which loop is adapted to surround the broom-handle. The arrangement is preferably such that when 50 the attachment is in position on the broom-handle the loop c and eye a' shall hold it toward the handle, while the eye a² shall hold it away from said handle, thus giving the required friction to hold the attachment in whatever position it is placed, or, in other words, to prevent it from slipping up and down too easily.

My invention constitutes a cheap and convenient means of keeping brooms off the floor 60 when not in use, and fully accomplishes the object specified.

Having thus fully described my said invention, what I claim as new, and desire to secure by Letters Patent, is—

1. The combination, with a broom, of a supporting attachment, C, secured to the broom-handle, and adapted to slide up and down on said broom-handle, and be thus caused to project beyond the lower end of the broom or 70 be withdrawn above it, substantially as set forth.

2. The combination, with a broom, of the attachment C, having loop c, and the eyes or loops a' a² on the handle, through which the 75 stem of said attachment passes, substantially as set forth.

3. The combination, with a broom, of a supporting attachment passing through eyes or loops attached to the broom-handle, said eyes 80 or loops being arranged, as specified, to press upon the stem of said attachment and prevent it from slipping up and down too easily, substantially as set forth.

In witness whereof I have hereunto set my 85 hand and seal, at Indianapolis, Indiana, this 4th day of October, A. D. 1882.

SAMUEL W. BARNETT. [L. S.]

In presence of—

C. BRADFORD,
E. W. BRADFORD.
